UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

SCRAPER LOADER SYSTEM.

1,408,080.

Specification of Letters Patent. Patented Feb. 28, 1922.

Application filed September 20, 1920. Serial No. 411,554.

To all whom it may concern:

Be it known that I, CHARLES E. DAVIS, a citizen of the United States, residing at Chicago, in the county of Cook and State of Illinois, have invented an Improvement in Scrapper Loader Systems, of which the following is a specification.

This invention relates to improvements in apparatus for handling loose material and more particularly to scraping devices for transporting coal from the working face of a mine to an entry for loading in mine cars. The object of the present invention is to provide a more efficient apparatus of the class above described and an improved method of operating the same.

My invention may best be understood by reference to the accompanying drawings in which Figure 1 is a view of the scraper or scoop forming part of my invention.

Figs. 2 and 3 are diagrammatic views of a mine room having a scraper loader system installed therein, illustrating the use of my invention.

Figures 4 and 5 are enlarged views showing the scraper in various operating positions in one corner of the mine room.

My invention is particularly adaptable to assist in the so-called "scraper-loader" system of coal handling, of which a typical apparatus is illustrated in Figures 2 and 3. A scraper 1 is provided with a head rope 2 and tail rope 3, each of said ropes being operated by a suitable hoisting engine of the usual type (not shown), usually situated outside of the mine room, in the entry or gallery 4. The head rope 2 is adapted to be led over a detachable sheave 5 anchored in one corner of the room adjacent the working face 6.

The tail rope 3 is led around the stationary sheave 7 anchored in the opposite corner of the room, and from thence around suitable guiding sheaves to the hoisting engine. In starting the loading operation, the scraper is dragged by the tail rope 3 to the far corner of the room adjacent the stationary pulley 7. The tail rope 3 is then allowed to run free, and the head rope 2 is led around the detachable sheave 5. With this arrangement, when the head rope is pulled by the hoisting engine, the scraper moves along the working face 6 of the mine wall, to collect the loose material adjacent thereto, and thence turned toward the entry by detaching the head rope 2 successively from the sheave

5, and a second detachable sheave 8. The head rope 2 is then disengaged from the sheave 8, and the straight pull is exerted on the scraper to move it outwardly to the entry where it is loaded into cars in the usual manner.

A deflector or guide pulley 9 is usually placed in a position near, but spaced from the detachable sheave 5 in order to maintain the scraper in a path along the side of the room in its movement to and from the entry, as a large portion of the room is usually occupied with waste material or mine props around which the scraper must move. When the head rope 2 is detached from the sheave 7 and the scraper moves toward the entry, the tail rope 3 engages the deflector or buffer guide 9.

A preferred construction of scraper used with systems such as described is illustrated in Figure 1, which comprises a bottomless body portion 10 having substantially upright side walls 11, 11 converging at the rear of the scraper in a rounded rear end portion 12.

One difficulty has been met with in manipulating the scraper to load the coal in the far corner of the room adjacent the sheave 7, when the scraper is in starting position. The scraper is necessarily of considerable weight, and must be shifted laterally to several positions in order to gather the loose coal in this corner. Another difficulty has been in scraping close to the working face 6, which heretofore has been accomplished by directing the scoop toward the face before the pull is exerted on the head rope.

In the present invention, the tail-rope connection with the scraper comprises a suitable link 13 attached to the tail rope 3, and movable along a suitable rod or bar 14 having suitable connections at one end adjacent the approximate longitudinal center line of the scraper, and at the other end on the side of the scraper nearest the working face of the mine. The arrangement is such that the link 13 may freely move along the bar 14 during the operation of the scraper as will hereinafter more fully appear. It is preferable to provide a rearwardly and outwardly extending portion or notch 15 on the bar 14 at a point substantially on the longitudinal center line of the scraper as shown. I also provide the scraper with a hook 16 at

tached to the side thereof opposite the working face of the mine, and preferably arranged near the top edge of the scraper as shown, so as to pass above the deflector or 5 buffer guide 9 as the scraper is moved around the latter. A rearwardly extending bearing portion or shoe 17 may also be provided integral with said hook, and extending rearwardly around the rear end of the 10 scraper.

With the apparatus above described, a suitable jack or similar device 18 is fixed in position near the sheave 7 and to one side of the normal path of travel of the 15 scraper as it moves from the deflector guide 9 toward the sheave 7, as shown in Figure 3. As the scraper is moved rearwardly after depositing its load in the entry, the link 13 if not already engaged in the notch 15, is 20 moved automatically toward the said notch so as to engage therein, because of the shape of the scoop, and the drag of the head rope 2 which is drawn thereafter. At all events, when the scraper reaches the position shown 25 in Figure 3, the link 13 would be drawn into the said notch 15 in position to drag the scraper rearwardly substantially along its longitudinal axis, as shown in full lines in Figure 4. As the scraper moves rearwardly 30 it is brought into contact with said fixed member 18 at some point along the bearing member 17, substantially as indicated in dotted lines in Figure 4, and is deflected slightly toward the face of the mine, until 35 the hook 16 becomes engaged with the fixed member 18. As soon as the hook becomes thus engaged, it will be observed that movement of one side of the scraper will be retarded, but a continued pull on the tail rope 2 will cause the scoop to rotate about the fixed member 18 as an axis, while the link 13 of the tail rope slides along the rod 14 and around to the side of the scoop and 40 finally reaches a position as shown in Figure 45 5, in which the scoop is turned in a position at an angle to the face. From this position, which is called the starting position, the movement of the scraper is reversed by releasing the tail rope 3 and pulling on the 50 head rope 2. It will thus be seen that the scraper is positively turned in position to gather a large proportion of coal immediately adjacent the sheave 7, thereby minimizing the lateral shifting of the scoop, and the 55 shoveling ordinarily necessary in order to gather all the loose coal in this corner. This feature is particularly advantageous in gathering coal under a low roof where difficulties

of handling the scoop, and shoveling of the loose material are increased by the limited 60 head-room available.

Although I have described a specific loading system with which my invention is particularly adaptable, it will be understood that my invention may be applied to other 65 loading systems, as for instance, in which the movement of the scraper may be in one direction without turning, but in which it is equally necessary to direct the scraper toward the mine wall in its initial movement. 70 Furthermore, it will be understood that many variations may be made in the specific construction and arrangement of the tail rope connections without departing from the spirit and scope of my invention. 75

Having described my invention, what I claim as new and desire to cover by Letters Patent, is:

1. In a scraping apparatus, a scraper provided with a rope having a movable connection with said scraper, and means for retarding the movement of said scraper at a point on one side thereof during its normal movement in one direction. 80

2. In a scraping apparatus, a scraper provided with a head rope, and a tail rope having a slidably connection along the rear end and one side of said scraper, and a projection on the other side of said scraper adapted to engage a fixed support. 85

3. In a scraping apparatus, a scraper provided with a head rope, a tail rope, means affording movable connection of said tail rope and said scraper, comprising an arcuate guide member extending from one side of 95 said scraper substantially to the longitudinal center line at the rear end thereof, a coacting link attached to the tail rope, and a projection on the opposite side of said scraper adapted to engage a fixed support. 100

4. The method of handling a rope operated scraper device which consists in positioning a fixed member at a predetermined position in the rearward line of movement of the scraper, pulling the scraper rearwardly to engage said member at a point on one side of said scraper, and continuing the pull on said scraper, with said fixed member as an axis, into a position at an angle to the normal line of movement of 110 the scraper. 105

Signed at Chicago, in the county of Cook and State of Illinois, this 17 day of Sept., A. D. 1920.

CHARLES E. DAVIS,
